UNITED STATES PATENT OFFICE.

HENRY ANDREW YOUNG, OF WINNIPEG, MANITOBA, CANADA, ASSIGNOR OF ONE-HALF
TO PHILIP H. BROTMAN, OF WINNIPEG, MANITOBA, CANADA.

DOOR-LATCH.

1,242,301.

Specification of Letters Patent.

Patented Oct. 9, 1917.

Application filed May 24, 1917. Serial No. 170,661.

To all whom it may concern:

Be it known that I, HENRY ANDREW YOUNG, a citizen of the Dominion of Canada, residing at the city of Winnipeg, in the Province of Manitoba, in the Dominion of Canada, have invented certain new and useful Improvements in Door-Latches, of which the following is a specification.

This invention relates to latches or fasteners more particularly useful in connection with screen and storm doors, and the objects of the invention are to provide simple, cheap and novel means for the purpose which are effective both as a latch and as a temporary lock.

With these objects in view the invention consists in the novel combination of parts and method of making the same, first fully described in the following specification and then more particularly pointed out in the appended claims, reference also being had to the accompanying drawings forming part hereof in which similar characters of reference indicate similar parts throughout the different views, and in which—

Figure 1 shows the device in operative position in connection with a door, the latter being in section to show the latch support or box mortised thereinto.

Fig. 2 is a view of the latch member proper, from above.

Fig. 3 is a separate view of the latch retainer or locking member.

Fig. 4 shows the stop with locking member or keeper operatively connected therewith.

Fig. 5 is a section taken on the line 5 in Fig. 4.

Fig. 6 shows the blank from which the stop is formed.

Fig. 7 is the blank from which the box support for the latch is formed.

Fig. 8 shows the rear end of the box or latch support when completed.

Fig. 9 is the face plate used on one side to maintain the position of the box in the door and add to the appearance of the finished article.

The whole device comprises first the box A in which the latch B is pivotally supported, and which is set in a mortise through the door as shown in Fig. 1. This box I prefer to make from a blank stamped from a piece of flat metal to the shape shown in Fig. 7, this being bent on the dotted lines 2 to form the top 3 and sides 4 of the box, and on the

dotted lines 5 to bring the edges 6 and 7 together to form the bottom. The semicircular marginal portions 8 are then turned out on the dotted lines 9 to form flanges adapted to lie flat against the stile of the door.

The edges 6 and 7 may be joined together by solder or other means or they may merely meet as shown in Fig. 8 this being an immaterial point as they are secure in either case, when in position in the door.

The portions 4 of the blank are perforated to provide the rivet holes 10 which register when the parts are folded, and the semicircular flange portions are perforated to provide the screw holes 11.

The latch member B I prefer to form from a single piece of wire, one end being turned around horizontally to form a circular handle 12, the intermediate portion of the wire being curved down from the handle 75 then coiled perpendicularly to form a rivet hole, the coil being indicated as 13, the wire then curving up and sharply down to form a hook 14, then curving out around the front of the bill 15 to form a finger grip 16 by 80 which the latch may be lifted, then down over the top of the hook to form a recess 17, and then back in a long over curve to form a spring 18 projecting into the box A and bearing against the under side of the top 3 85 thereof under compression.

The latch member B is pivotally mounted in the box A by a pivot or rivet 19 which passes through the openings 10 in the sides 4 and through the coil 13 on the latch.

A stop C is formed from the blank 20 by bending the marginal portions 21 back on the dotted lines 22 to form flanges having the apertures 23 formed in each in line with those in the other. A keeper 24 is formed 95 from a single piece of wire as shown in Fig. 4, the rabbit portion 25 of the blank 20 being curled around the ends 26 of the keeper to form a hinge connection.

The box A is secured to the door by the 100 screws 27 passed through the openings 11 in the flange portions 8, and the plate 28, (Fig. 9) preferably fits over the opposite end of the box and is secured to the door by the screws 29.

In Fig. 1 it will be noted that the stop C is secured to the jamb 30 of the door opening, by the screws 31 which pass through the openings 23 in the flanges 21, that is to say, through the openings in both flanges, the 110

stop standing at an angle so that the face thereof forms an incline up which the bill 15 of the latch member rides until it hooks over the curled loop 25 at the top of the stop, the hook being impelled to this by its spring portion 18. The keeper 24 is then rotated around the finger grip 16 to come to rest in the recess 17 and to so lock the latch. To release the latch the keeper is reversed and pressure used to either lift the finger grip 16 10 or to depress the handle 12, the spring 18, owing to its length, opposing but slight resistance.

The stop C, being formed with a flange member 22 on each side, through both of which the screws pass, is made suitable for either a right or left hand door without change.

Having thus fully described my said invention, what I claim as new and desire to secure by Letters Patent is—

1. In a device of the kind described, a single piece of wire shaped to form a latch having a handle at one end, a hook at the other end and a coil intermediate the ends, the said wire being looped around the front and over the top of the hook to form a finger grip and then extended rearwardly to form a spring.

2. In a device of the kind described, a single piece of wire bent to form a latch having a horizontal circular handle at one end, a hook at the other end, a coil intermediate the ends, a loop around the hook, a depression at the end of the loop behind the head of the hook and a rearwardly extending spring.

3. A door latch formed from a single piece of wire turned at the end to form a horizontal circular handle, then turned down and coiled to form an opening for a pivot, then curved up and sharply down to form a hook, then looped forwardly out around and over the top of the hook to form a finger grip ending in a depression merging into a rearwardly extending over curving spring.

4. A device of the kind described comprising a box or casing having a top and sides and a pivot element carried by the sides crossing the space intervening there-

between; a latch formed from a single length of wire coiled around the pivot and further shaped to have a handle, a hook and a spring extending rearwardly from the hook into the casing and bearing against the under side of the top thereof.

5. A flat metallic blank shaped to form a casing having apertured sides and flanges integral therewith by which it may be secured in a door; a pintle inserted through the apertures and crossing the space intervening between the sides of the casing; a latch formed from a single length of wire coiled around the pintle and further shaped to have a handle, a hook and a spring above and extending rearwardly from the hook into the casing and operating thereagainst to maintain the hook normally depressed.

6. A device of the kind described comprising a rectangular casing adapted to be secured in a door and having a pivot crossing the space between the sides thereof; a latch formed from a single length of wire coiled around the pivot and further shaped to provide a handle and a hook having a loop passing forwardly therearound to form a finger grip, a depression behind the head of the hook and a spring extending back into the casing.

7. In a door fastening, the combination with a stop secured to the jamb of the door frame at an outward inclination from the perpendicular and a loop swingingly mounted on the stop, of a latch pivotally mounted in the door and formed from a single length of wire shaped to provide a hook having a loop passing forwardly therearound, a depression at the end of the loop behind the head of the hook and a spring operative to maintain the hook normally yieldingly depressed, the loop on the hook being adapted to ride the inclined face of the stop when the door is being closed and till the hook engages the stop, and the loop on the stop being adapted to be rotated to rest in the depression behind the hook to maintain the engagement of the hook with the stop.

In testimony whereof, I affix my signature.

HENRY ANDREW YOUNG.
